UNITED STATES PATENT OFFICE.

HERMAN R. FREUND, OF BROOKLYN, NEW YORK, ASSIGNOR TO INTERTYPE CORPORATION, OF BROOKLYN, NEW YORK, A CORPORATION OF NEW YORK.

MATRIX DISTRIBUTOR FOR TYPOGRAPHICAL MACHINES.

Application filed August 8, 1924. Serial No. 730,898.

The present invention relates to improvements in typographical machines and more particularly to those of the class wherein two or more magazines containing respectively different fonts of matrices are used, and in which distribution of the matrices to the different magazines may take place concurrently from a single distributing bar.

The primary object of the invention is to provide novel and improved means whereby mixed matrices or matrices belonging to different fonts may be distinguished, separated and directed to the appropriate channels of their respective magazines with speed, facility and certainty.

To these and other ends the invention consists in certain improvements and combinations and arrangements of parts, all as will be hereinafter more fully described, the features of novelty being pointed out particularly in the claims at the end of the specification.

In the accompanying drawings:—

Figure 1 is a perspective view, partly in section, illustrating a portion of the matrix distributing means of a typographical machine embodying matrix distinguishing and separating means constructed in accordance with the present invention.

Figure 2 is a vertical cross section, taken substantially on the line 2—2, Fig. 1, looking in the direction of the arrow, showing the means by which matrices are directed to properly engage the separating means.

Figure 3 is a perspective view of a section of the separating rails, showing the method of constructing them.

Figure 4 is a perspective view of a standard form of matrix containing a single straight vertical groove through the side wall thereof.

Figure 5 is a perspective of a standard form of matrix having a curved groove in the side wall thereof.

Figure 6 is a sectional view showing diagrammatically the manner in which matrices having a curved groove therein are engaged and withdrawn by the separating rails from the delivery throat and directed into a throat leading to the upper magazine.

Figure 7 is a view similar to Fig. 6, showing diagrammatically the manner in which matrices having a straight or vertical groove

are distinguished and separated by the separating rails from those having a curved groove and are directed into a throat which leads to the lower magazine.

Figure 8 is a perspective view of a matrix which is of standard form but has its directing ears or lugs set in from its side walls.

Similar parts are designated by the same reference characters in the several views.

The present invention is applicable generally to typographical machines of the kinds employing circulating matrices which are stored in magazines to be delivered therefrom for assembly in a line preparatory to the making of a cast therefrom, after which the matrices are returned to the magazines through distributing mechanism. The invention, however, is more particularly applicable to typographical machines of the well-known linotype class, and more especially to machines of that class which are constructed to contain two or more magazines for matrices belonging to different fonts, and which employ a single distributor bar for the delivery of the mixed matrices or the matrices belonging to the different fonts to their magazines. The embodiment of the invention shown in the present instance is adapted for use in connection with a machine of this class using two magazines and a single distributor bar for distributing the matrices to both magazines, but it is to be understood that the invention is not restricted to the precise construction shown as equivalent constructions are contemplated, and such will be included within the scope of the claims.

In the present instance 1 and 2 represent the upper ends of the upper and lower superposed and downwardly inclined matrix magazines. These magazines are adapted to contain respectively matrices belonging to different fonts, and the matrices may be delivered from the lower or forward ends of these magazines, as required, by actuation of the usual escapement and keyboard mechanism, such as is generally used for such purposes in machines of this general class. The top and bottom plates of each magazine may be grooved, as shown, to receive the lugs or ears of the matrices, thus providing separate channels which receive and guide the matrices during their entry

and descent through the magazines. The usual distributor bar 3 employed for distributing matrices belonging to the different magazines may be of the kind usually employed in machines of this particular type, it being located, as usual, above and to the rear of the upper rear matrix receiving ends of the magazines.

- The purpose of the present invention is 10 to provide means for distinguishing and separating matrices belonging to different fonts. For this purpose I have provided in the side walls of the matrices, distinguishing grooves, these distinguishing grooves in 15 matrices belonging to different fonts being different, but such grooves are the same for matrices belonging to the same font. For example, in Figure 4 the matrix m is provided with a straight or vertical groove m^4 in one of its side walls, such groove leading from the top to the bottom of the matrix; and in Figure 5 the matrix m^1 is provided with a curved or arcuate groove m^5 in one of its side walls, 20 the upper and lower ends of this curved groove corresponding in position and relation with the groove m^4 in the matrix containing the straight or vertical groove, as 25 shown in Figure 4.
- 30 In Figure 8 I have shown a matrix m^2 which has, in recent years, come into common use in which the guiding ears or lugs m^{10} are offset from each of the flat sides of the body of the matrix, and this form 35 of matrix is shown provided with a circular groove m^6 in one of its side walls which corresponds with the curved groove m^5 in the matrix m' shown in Figure 5, but it is to be understood that other fonts containing 40 matrices of this particular form may contain a straight groove like the groove m^4 in the matrix m , Figure 4, for separation and distribution thereof to another magazine.
- 45 Referring now to Figure 1, the standard distributor bar 3 together with the screws 4 are shown, serving to conduct the matrices for delivery to the separating channels of the magazines by the combinations of teeth 50 in the upper ends of the matrices as shown, in conjunction with the permuted ribs on the distributor bar. As such distribution is of the usual form a detail of its operation 55 is not necessary herein.
- 55 As the matrices are delivered from the distributor bar, they pass into the upper end of the throat 5 of what has been generally termed the channel entrance 6 of a line casting machine, whereby and through which 60 they are diverted from their vertical delivery into an oblique path for delivery to the downwardly and forwardly inclined magazines.
- 65 According to the present invention, this channel entrance is extended and utilized

for a separating means in the following manner:

When the matrix m (Fig. 4) is delivered from the distributor bar 3 it passes directly into the upper end of the throat 5 of the channel entrance 6, the channel entrance being provided with the usual separating plates 7 appropriately spaced to keep the matrices in vertical position for delivery to the magazines, it being understood that 75 there are a series of these plates of a like character to provide for the delivery of an entire font of matrices. As each matrix m is delivered into the throat 5 it immediately comes into contact with the directing 80 rails 8 which the falling matrix engages by the ears or lugs on its corners and is guided thereafter entirely by its ears or lugs.

It may be noted in Figure 2 that the upper ends of the rails 8 are bevelled to 85 provide flared openings at the entrances of the channels formed between them in order that the lugs or ears of the matrices may readily enter the channels and thus bring the respective matrices under the control of 90 the rails 8. It is also to be noted that these rails 8 project from the opposite sides of the channel entrance in order that a matrix having the lugs or ears arranged as shown in Figure 8 may be accommodated in the regular 95 operation of distribution. In other words, it is immaterial whether the lugs or ears of the matrices are flush with either or both sides of the matrices, as in Figures 4 and 5, or whether the lugs or ears are offset 100 inwardly from the sides of the body, as in Figure 8, as the means for preparing the matrices to meet the separating means, hereinafter described, are present in each channel of the channel entrance.

Immediately after the matrix is in control in the rails 8, it is then in position to meet the font separator 9, which is positioned in the throat 5 to meet the matrices as they pass along the rails 8 from the distributor bar 3. A section of the font separator is shown in Figure 3, but it is to be understood that although this section is only shown with three openings, the bar is of sufficient length to correspond with the number of distributing points on the distributor bar and the number of channels in each magazine and it is fitted into an opening in the front of the channel entrance so that it forms substantially a part of the front 110 wall thereof. The separator is provided with a series of rails 10 which project into the respective channels of the channel entrance and are curved or arcuate in conformity with the curved grooves m^5 and m^6 115 of the matrices m' or m^2 . Each rail 10 is provided with an opening 11, these openings being arranged uniformly throughout the separator and substantially tangentially 120 of the respective rails for a purpose which 125 130

will be hereinafter described. Each of the rails 10 below the opening 11 is slightly pointed, as at 12, for purposes which will also be described later.

5 As the matrices m' are directed, as described, to the throat 5 and are guided under the control of their guiding lugs along and between the rails 8 they meet the separator at the top 10^a of the respective separating rails. This point of contact of each separating rail is so positioned in the respective matrix channel of the channel entrance that the matrices which are fully under control in each direction in their channels of the rails 8 will properly present the grooves in their side wall to the point 10^a of the respective separating rails. Assuming, for example, as in Figure 6, that the matrix m has passed through the channels 10 between the rails 8, and that the groove in the matrix has come in contact with the point 10^a of the separating rail, it is shown therein that the tendency of the matrix is to follow the curved rail 10, the matrix 20 bridging or passing the opening 11 to the lower section of the rail 10. The upper end of the lower section of the rail 10 adjacent to the opening 11 is tapered to catch and direct this matrix so that it will follow the curved rail 10 throughout its distance which leads the matrix for delivery to the upper magazine 1.

If, however, the matrix delivered from the distributor bar D had been one like the matrix m (Figure 4) in which the groove in its side was vertical, such matrix when coming in contact with the separator 9 at the point 10^a, as shown in Figure 7, would have passed directly through the opening 11 on the rail 10 into the lower section of the throat 4 and thus be led into the lower magazine 2.

The invention enables matrices belonging to different fonts to be distributed to the appropriate channels of their respective magazines from a single distributor bar with the same speed, facility and certainty as has been the practice in machines where only the usual or standard matrices are used.

50 The matrix separating means which receives the matrices belonging to the different fonts from the distributor bar, automatically distinguishes and separates the matrices and then directs them into their appropriate magazines. The structure may be readily applied to typographical machines, and especially to those of the linotype class, as it may be accommodated within the channel entrance through which the matrices pass 55 from the distributor bar to the magazines.

I claim as my invention:—

1. In a typographical machine having two magazines each containing a font of matrices, the matrices of one font having a 60 curved distinguishing groove in a flat side

of the body thereof and the matrices of the other font having a straight groove in the flat side of the body thereof, the openings of the distinguishing grooves in the matrices of the different fonts being in the same relative position on the matrices, a distributor, and a channel entrance for directing the matrices from the distributor to the magazines; a matrix separating rail embodying means for so cooperating with the matrices 70 as to guide those having curved grooves in one direction and those having straight grooves in another direction.

2. In a typographical machine having two magazines each to contain a font of 80 matrices, a distributor to deliver matrices to the upper end of each of the magazines, guides within each channel of the channel entrance, directing means within the channels to assume control of the falling matrices 85 by their lugs or ears and to direct the flight of the matrices, and a separator to which the matrices are directed and which is arranged to engage in a curved distinguishing recess in the flat side of matrices of one font 90 and to deliver such matrices to an upper magazine and having a cut-away portion arranged to permit those matrices having a straight groove throughout to disengage 95 therefrom and to be delivered to a lower magazine.

3. In a typographical machine having a plurality of magazines adapted to contain different fonts of matrices, those of one font having a straight groove and those of 100 another font a curved groove in a side thereof; means for directing the matrices belonging to the different fonts through common paths, and a matrix separator embodying rails arranged to enter the grooves in the 105 sides of the matrices of different fonts and having cut-away portions intermediate their length, said rails being curved to engage the curved grooves in the matrices of one font and thus direct such matrices along 110 the rails to one magazine, and causing the matrices having the straight grooves therein to disengage from the rails through the cut-away portions thereon for delivery to another magazine.

4. In a typographical machine having a plurality of relatively superposed magazines one to contain a font of matrices each having a curved groove in a side thereof and another to contain a font of matrices each having a straight groove in a side thereof; a channel entrance to receive such matrices and having guides for directing the matrices, and a matrix separator embodying rails which extend into the paths of the matrices 120 and are arranged to engage in the grooves in the sides thereof, said rails being curved to conform substantially with the curved grooves of certain of the matrices and having each a cut-away portion to permit dis- 125 130

engagement therefrom of the matrices having the straight grooves.

5. In a typographical machine having a plurality of relatively superposed magazines one to contain a font of matrices each having a curved groove in a side thereof and another to contain a font of matrices each having a straight groove in a side thereof; a channel entrance to receive such matrices and having guides for directing the matrices, and a matrix separator embodying rails which extend into the paths of the matrices and are arranged to engage in the grooves in the sides thereof, said rails being curved 10 to conform substantially with the curved grooves of certain matrices and operative to support such matrices and direct them into one of the magazines, and each rail having a portion cut away on the line of a chord 15 to cause matrices having a straight groove

to pass the rails without traversing the lengths thereof.

6. In a typographical machine embodying a single distributor and two magazines each containing a font of matrices, the matrices belonging to one font having a curved groove therein and the matrices belonging to the other font having a straight groove therein, means including a curved rail cut away on the line of a chord interposed between the distributor and the magazines whereby matrices having a curved groove will follow said rail and thus be directed to one magazine and matrices having a straight groove will be permitted to clear the rail through the cut-away portion thereof and thus be directed to another magazine.

In testimony whereof I have hereunto set my hand.

HERMAN R. FREUND.
